UNITED STATES PATENT OFFICE.

JOHN N. MARQUETTE, OF BALTIMORE, MARYLAND, ASSIGNOR OF ONE-THIRD TO JAMES D. M. MARQUETTE AND ONE-THIRD TO PETER J. NELSON, OF BALTIMORE, MARYLAND.

CAR-DOOR.

No. 872,953.

Specification of Letters Patent.

Patented Dec. 3, 1907.

Application filed December 19, 1906. Serial No. 348,546.

To all whom it may concern:

Be it known that I, JOHN N. MARQUETTE, a citizen of the United States, residing at Baltimore, in the State of Maryland, have 5 invented certain new and useful Improvements in Car-Doors, of which the following is a specification.

This invention relates to improvements in car doors and is particularly an improvement on that class of doors which are hung so as to be moved in and out of the frame or opening and to also be moved laterally with respect to said opening.

The object of the invention is to provide 10 an improved construction of mechanism of this class.

The improvements are illustrated in the drawing herewith, in which—

Figure 1, represents a side elevation of the 20 car body and my improved door and operating mechanism attached thereto. Fig. 2 is a vertical section through the same,—the section being taken on the line 2—2 of Fig. 1. Fig. 3 is a horizontal sectional view 25 through the body, door and operating mechanism as the same would appear on the line 3—3 of Fig. 1. Fig. 4 is a similar view with the exception that the door is shown in the laterally-moved position as it would appear 30 on the line 4—4 of Fig. 1, and Fig. 5 illustrates an enlarged sectional detail of the operating arm and coacting devices.

Referring to the drawings by numerals, 1, designates the side of the car body or the 35 receptacle; 2, the opening therein and, 3, the frame around said opening. In the present instance the opening in the frame is beveled.

Above the opening the body is provided 40 with an upper horizontally-extending rail, 4, and below said opening said body is provided with a lower horizontal rail, 5. These rails may be attached to the body in any suitable manner but in the present instance a plurality 45 of blocks, 6, are interposed between the rails and body whereby to sustain said rails in an off-set or spaced position from the body.

A metallic strip, 7, is secured close against 50 the side of the car body about midway between the two rails and this strip serves to keep the door from frictional contact with the body during its lateral travel as will presently appear. An angle plate, 8, is also 55 attached to the body and serves as a stop.

against which the door contacts to limit its lateral travel.

The door, 9, may be of any suitable construction but in the present instance it is provided with beveled horizontal and vertical edges, 10, to conform to the shape of the opening, 2, in the body so as to make a tight joint or closure when forced into the opening. By the door being forced tightly into the door-opening, and the outer surface of the door flush with the outer side of the car there will result a complete exclusion while the car is in motion, of sparks, and hot particles of cinders from the locomotive.

Clips, 11, take over or loosely engage the 70 upper rail, 4, and are provided with lateral perforated extensions, 12. These clips may be constructed in any suitable manner so long as they securely engage the upper rail and are slidably thereon. Vertical shafts, 75 13, and, 13^a, have their upper ends projecting through the said perforations in the clips and are rotatably held therein by means of nuts, 14, which engage their upper projecting ends. These clips, 11, are designed merely as traveling guides for the upper end 80 of the door and are not employed to sustain the door as the latter is supported at the bottom on carriages as will presently be described.

Adjacent the bottom of the door and mounted on the lower rail, 5, are a plurality of traveling carriages or supports, 15. These carriages are mounted on grooved rollers, 16, which travel on the rail, 5, and their flat 90 upper surfaces, 17, are substantially flush with the lower edge or sill of the opening in the car-body, as clearly seen in Fig. 2. Lateral projections, 18, are provided on the carriages and said projections are perforated so as to receive the lower ends of the two vertical shafts. A bar, 19, extends horizontally 95 between the carriages and connects the latter so as to keep them properly spaced.

Adjacent their ends the vertical shafts are 100 each provided with a sleeve, 20, from each of which an arm, 21, projects laterally. These sleeves and arms are rigid with the shafts and are rocked in a horizontal plane with the latter as will presently be described. 105 The ends, 22, of these arms are bifurcated and are pivotally connected to brackets, 23, which latter are rigidly secured to the door.

An operating bar, 24, is rigidly carried on the shaft, 13, and said bar carries a pivoted 110

arm, 25, at its end. This pivoted arm is provided with a perforation through which a rigid stud, 26, on the door projects when the pivoted arm, 25, is swung against the side of the door, as in Figs. 1 and 5. A pin, 27, carried on a chain, 28, is passed through a hole in the rigid stud and serves to hold the arm, 25, against the door only when the latter is closed.

10 A locking lever, 29, is pivotally mounted on one of the lower arms, 21, adjacent the shaft, 13^a, (see Figs. 1, 3 and 4) and this lever extends inwardly and is provided with a perforation in its end which takes over a 15 horizontal stud, 30, also on the door and preferably adjacent the bottom thereof. A pin or seal, 31, may be attached to the stud, 30, to prevent the unauthorized opening of the door without detection.

20 In the operation of opening the door the seal or pins, 27, and, 31, are first removed and the locking bar, 29, is drawn outwardly from engagement with the stud, 30. The operator will then grasp the knob on the 25 pivoted arm, 25, and draw said arm away from the door as indicated in broken lines in Fig. 5, and the preliminary outward movement of the arm will first release the latter from the stud, 26, on the door while the 30 further outward movement of said arm will rotate the shaft, 13. The rotation of this shaft will cause the arms, 21, at the upper and lower ends of the shaft to swing outwardly. The outward swinging of the arms, 35 21, of shaft, 13, will cause the rotation of the other shaft, 13^a, the same as though the two shafts were directly connected. In swinging outwardly the door is deposited onto the flat top surfaces of the traveling 40 carriages, 15, and the weight of the door is sustained by said carriages while the clips, 14, at the top of the door merely serve to maintain the door in a vertical position and

also act as bearings for the upper ends of the shafts, 13, and, 13^a. After the operating 45 arm, 25, has been drawn outward sufficiently to deposit the door on the carriages, 15, further pull thereon will cause the carriages, shafts and door to travel laterally along the rail, 5. It will thus be seen that the operations of drawing the door outwardly and laterally is accomplished by the single outward operation of the arm, 25.

Having thus described my invention what I claim as new and desire to secure by Letters Patent is,—

1. The combination with the car-body having a door-opening, of a rail on the car-body below said opening; carriers traveling on said rail and having a flat top surface substantially flush with the bottom of the said door-opening; a door; brackets on the door; vertical shafts having their lower ends rotatably mounted on the said carriers, and arms attached to the vertical shafts and pivotally connected with the said door-brackets.

2. The combination with the car-body having a door-opening, of the traveling carriers at the side of the body; shafts having their lower ends engaged with said carriers; 70 bearings at the upper ends of the shafts for maintaining them in a vertical position; a door; arms rigid with and carried by the said shafts and pivotally connected with the door, and a bar, 24, also rigid on one shaft 75 for rotating the shaft to cause the door to move from the door-opening onto the carriers, and said bar having a jointed arm to be fastened to the door.

In testimony whereof I affix my signature 80 in presence of two witnesses.

JOHN N. MARQUETTE.
